UNITED STATES PATENT OFFICE.

JOHN A. BARRETT, OF BROOKLYN, NEW YORK, ASSIGNOR TO THE JOHN A. BARRETT COMPANY, OF BALTIMORE CITY, OF MARYLAND.

CATCH FOR BOXES, &c.

SPECIFICATION forming part of Letters Patent No. 403,029, dated May 7, 1889.

Application filed February 8, 1888. Serial No. 263,352. (No model.)

To all whom it may concern:

Be it known that I, JOHN A. BARRETT, a citizen of the United States, and a resident of Brooklyn, in the county of Kings and State of New York, have invented a certain new and useful Catch for Boxes, &c., of which the following is a specification.

My invention relates to a catch or lock intended more especially for application to boxes generally, to bags, or other receptacles formed in two parts which are to be closed together and held closed or formed with an ordinary cover.

The object of the invention is to provide a simple, cheap, and effective fastening; and the invention consists in the combination, with the two parts of the box or similar receptacle that are to be fastened together, of a sleeve or collar and a lug or pin, either one adapted to rotate, and secured, respectively, to the two parts of the receptacle, the sleeve or collar being cut away at one point to permit the pin when in a particular position to pass it when the parts are being closed together, after which a movement of rotation of one or the other element of the lock or catch will hold them fastened, one of the elements being on the handle of the box.

The invention consists also in the combination, with the rotating member of the catch or lock, of a spring applied, as will be herein-after described and shown, so as to prevent rotation to the point of opening excepting upon the application of a positive force by the hand.

In the accompanying drawings, Figure 1 is a side elevation of a box furnished with a catch or lock constructed in accordance with my invention. Fig. 2 is a plan of the same. Fig. 3 is an end elevation of the box, the catch being shown in cross-section taken on the line X X, Fig. 2. Fig. 4 shows the same view of the catch enlarged, the parts being arranged in locked position. Fig. 5 shows the parts unlocked and the two halves of the box separated. Fig. 6 is a plan of an equivalent form of my invention wherein the lug or pin is made to rotate instead of the sleeve or collar. Fig. 7 shows in side elevation a box with a spring applied, so as to prevent accidental rotation of the rotating part of the catch. Fig.

8 is an enlarged view in cross-section on the line Y Y, Fig. 6.

A B indicate the two parts or halves of the box which are to be fastened together, and C 55 C two lugs or brackets fastened to the upper half, A, and carrying the two rotatable collars or sleeves E, which are adapted to turn in said brackets in any suitable manner. They are in the present case connected by a bar, 60 H, which is formed as a handle by which the box may be transported. Secured to the other part of the box B are two lugs or pins, F, which in the present case are formed upon and project laterally from the brackets or ears 65 D. The sleeves or collars E are cut away at the point M, as shown more particularly in Figs. 4 and 5, so that when the two halves of the box are brought together, with the sleeve or collar E turned to the position shown in 70 Fig. 5, the sleeve may pass the lug F, allowing the two parts A B to come together, after which a movement of rotation of the sleeve E, by means of the handle or other device, will bring the parts into the relation shown in 75 Figs. 3 and 4, wherein, as will be obvious, the two parts will be held against disengagement. The box may then be transported by the handle H without any danger of opening. When the box is laid down in the position shown in Fig. 80 3, a movement of rotation of the handle H in direction of the arrow, so as to produce approximately a quarter-turn of the sleeve, will bring the opening M so that it will register with the lug or pin F, and the top part, A, of 85 the box may then be lifted.

It is obvious that a second slot or opening, M', Fig. 4, might be formed opposite the first, so that the turning of the sleeve in either direction from the position shown in Fig. 3 90 would unlock the box; but for the sake of security I prefer to employ the sleeve with the single opening.

In order to prevent the rotating member from being turned to unlocking position accidentally, I provide a spring, G, applied, as indicated in Fig. 7, to be in the path of the rotating member or the part by which such member is rotated at or near the unlocking-point. By this arrangement if the box or receptacle 100 should be stood upon edge and the handle fall to the position shown in dotted lines, Fig.

7, the parts would not become unlocked, but could be unlocked by the application of a positive pressure by the hand sufficient to overcome the stress of the spring G.

5. In Figs. 6 and 8 I have shown the pin F as the rotating member of the combination, the sleeve or collar E being mounted upon the fixed bracket or ear C. In the position shown in Fig. 8 the parts are evidently locked 10 against any movement necessary in order to open the box A B; but by turning the pin F a quarter-turn approximately the pin and sleeve or collar will be brought into such position that they may be separated by the movement 15 of one or the other part of the box.

I do not limit myself to the precise form of sleeve and lug or pin, nor to the particular manner of mounting them. They must be, however, so arranged that one or the other of 20 them being on the rotating handle of the box may have a movement of rotation after the two are brought into juxtaposition by the closing of the box, the rotary movement of the handle being substantially in the plane of 25 movement of the parts of the box or case, and said sleeve being properly cut away to allow the pin to pass it, as described, in one position of rotation.

What I claim as my invention is—

30. 1. The combination, with a portable box,

bag, or other receptacle formed in two parts adapted to be closed together and having a carrying-handle permanently pivoted to one of said parts, of a locking device composed of a sleeve or collar cut away, as described, and a 35 lug adapted to enter said collar secured, respectively, to the two parts of the receptacle, one of the parts of said locking device being in operative connection with the carrying-handle and so arranged that when the handle 40 is swung into carrying position the lug and collar are locked against separation, substantially as described.

2. The combination, with the sleeve or collar cut away and the lug or pin, either adapted 45 to rotate or turn and secured, respectively, to the two parts of the box or other receptacle requiring to be secured together, of a spring, G, of any suitable form, placed in the path of the rotating element, so as to prevent the same 50 from being turned to unlocking position, as and for the purpose set forth.

Signed at New York, in the county of New York and State of New York, this 10th day of January, A. D. 1888.

JOHN A. BARRETT.
